UNITED STATES PATENT OFFICE.

FRED WAITE, OF OTLEY, ENGLAND.

FEEDING MECHANISM.

No. 913,929.

Specification of Letters Patent. Patented March 2, 1909.

Application filed March 30, 1907. Serial No. 365,546.

To all whom it may concern:

Be it known that I, FRED WAITE, a subject of the King of England, residing at Otley, in the county of York, England, have invented 5 certain new and useful Improvements in Feeding Mechanisms, of which the following is a specification, reference being had to the accompanying drawing, forming a part hereof.

The invention relates to automatic feeding 10 mechanisms such as are applied to printing presses and the like in order to feed sheets one at a time from a pile of sheets upon the feed table. Heretofore, in automatic feeders of this sort, it would often happen that more 15 than one sheet would be fed from the pile and delivered into the press at a single operation of the feeding mechanism.

The object of the invention is accordingly 20 to provide a feeding mechanism or device of this character in which the possibility of feeding more than one sheet at a time shall be reduced to a minimum.

The invention will be more fully described 25 hereinafter with reference to the accompanying drawings in which,

Figure 1 represents, partly in section and partly in side elevation, one embodiment of the improved feeding mechanism. Fig. 2 is a view of the same in rear elevation. Fig. 3 is 30 a view, in side elevation, of grippers and operative mechanism therefor to which the sheets may be delivered from the feeding mechanism. Figs. 4, 5, 6 and 7 are detail views, partly in section and partly in elevation, on 35 a larger scale, illustrating the successive positions of the parts during the feeding of a single sheet. Figs. 8 and 9 are respectively a broken front elevation and broken rear elevation of the parts shown in Fig. 4, and, Fig. 10 40 is a detail sectional view of some of the parts in the positions illustrated in Fig. 6. Fig. 11 is a detail view showing certain parts separate from the machine, for the purpose of more clearly illustrating the same.

In accordance with the present invention, 45 the pile of sheets to be fed is placed upon a feed table and is subjected to means at the forward and rear ends of the table for picking up, lifting or raising the front and rear ends 50 of the top sheets. These means are preferably pneumatic means, as will be described presently, and as soon as one of them oper-

ates to lift the corresponding edge of the paper, a check, such as a presser-foot, reaches underneath the sheet and down upon the remaining sheets in order to hold them while the top sheet is being delivered. As soon as these two operations have taken place, the means for raising the sheet at the other end of the table, which will be called the forward end as it is the end from which the sheet is delivered, operates to raise the forward end of the top sheet so that it can be seized and withdrawn from the feed table by the grippers. This being the general mode of operation, the particular parts of the present mechanism will now be described.

Above the feed table 1 and between the two side frames 2 are the forward and rearward means for picking up, raising or lifting 70 the top sheet preparatory to its delivery from the pile. These means preferably consist of rocking members 3 and 4 respectively, each provided with suction openings 5 whereby the edges of the sheet may be caught 75 and rolled or curled. The forward rocking member 3 may be mounted in end bearings 60 formed on movable boxes or trucks 6 situated on the free ends of two L-shaped arms 7 carried on a pivoted shaft 8 which, 80 through an arm 9, link 10 and arm 11, is operatively connected with a cam 12 upon a shaft 13 which constitutes the main shaft of the mechanism. In this way the rocker member 3 is raised and lowered at the proper 85 time. In order to rock this member, it is provided with a pinion 14 on one end meshing with a rack formed upon one of the L-shaped arms 7, and the boxes or trucks 6 are both provided with a pivoted arm 15 which 90 is operatively connected as shown with a cam 16 on the shaft 13 in order to effect the rocking and thereby the curling or rolling up of the edge of the paper at the proper time.

The rear rocking member 4 is provided 95 with bearings 17 on side arms 18 carried upon a rock shaft 19 pivoted in side standards 20 which are adjustably secured on a vertically reciprocating platform 21 by means of fixing bolts 22. In order to effect 100 the rocking of this member 4, it is provided with a pinion 23 which meshes with a rack 24 formed upon a bracket 25 horizontally movable upon one of the side bars 26 of the ma-

chine. This bracket is provided with a slot 27 which is engaged by a roller 28 upon one of the standards 20. It will thus be seen that as the platform 21 moves up and down the rack and pinion will effect the rocking of the member 4. It will also be seen that by simply unloosening the bolts 22, the side standards 20 and the bracket 25 can be readily moved toward or from the front rocker member 3 so as to adjust the device for different sizes of sheets. The raising and lowering of the platform is easily accomplished through a cam 61 on the main shaft 13 through a rod 33 and roller 33'. By comparing Figs. 4 and 5 it will be seen that when the platform 21 and standards 20 are lowered, the arms 18 will cause the pinions 23 to travel on the rack 24 (the latter being stationary) thus rocking the member 4. After the edge of the top sheet is raised or curled up by the rocker member 4, a presser-foot or other suitable check 29 reaches underneath this edge of the top sheet and bears down upon the remaining sheets, as heretofore explained. For this purpose, the presser-foot may be mounted upon a rock arm 30 having its bearings in the side standards 20 and provided with a roller 31 which cooperates with a cam 32 upon the shaft 19. A spring coiled around the rock arm 30 serves to keep the roller 31 in contact with the cam 32 and a spring coiled around the shaft 19 tends to hold the pinion 23 down upon the rack 24. As the platform 21 is raised and lowered to rock the member 4, the presser-foot will be brought into operative engagement with the pile of sheets by reaching down underneath the rear end of the top sheet which is raised or curled up by the rocker 4. (Figs. 5 and 10.)

The feed table 1 is mounted on a screw 34 guided vertically by bearings 34' and 35 provided in cross stays 36 of the frame, and by a sliding bearing 37 itself guided vertically on depending rods 38 fixed to the lower cross stay 36. In order to raise the table automatically as the sheets are fed from the top of the pile so as to bring the top sheet in operative position at all times, the screw 34 is provided with a nut 39 having ratchet teeth 40 upon its periphery, which teeth are adapted to be engaged by a spring plunger 41 which is operated by a cam 42 through the medium of a bell crank lever 43. As the plunger is thus operated, the nut is rotated to raise the table.

Between the end of the plunger and the operative connection to its actuating cam is a wedge-shaped or stepped piece 43', the position of which between the plunger and said operative connection depends upon the height or position of the top sheet, said wedge-shaped piece being connected through a system of multiplying levers 44 with a feeler arm 45 which rests lightly upon the top sheet. Thus the table is automatically moved upwardly according to the feeding of

the sheets and the rate of movement of the table will thus obviously be proportionate to the thickness of the sheets which are being fed. A hand wheel 46 may be provided to operate a chain gear 47 connected with the nut 39 whereby the table may be moved up or down independently of the automatic table raising mechanism.

For the purpose of bringing the pile of sheets upon the feed table into proper relation with the operative mechanism at the outset, the table may be provided with a front guide or guard 48 and a rear guide or guard 49, the latter being secured to the adjustable side standards 20 and thus movable back and forward with said standards. The front guide 48 is fixed and brings the forward ends of the sheets into proper position to be drawn up by the rocker 3 from which they are delivered to the grippers or other suitable mechanism. In the present case, suitable gripper mechanism is illustrated particularly in Fig. 3. It will be seen that grippers 50 are secured to a slide 51 which travels back and forth upon horizontal guides 52, being actuated from a crank disk 53 on the main shaft through suitable connecting links and levers. Fig. 7 indicates the position of the parts and the grippers just as the latter are receiving a sheet from the forward rocker 3. To permit the grippers to engage the sheet, this rocker is provided with recesses 54 at suitable intervals in its forward edge, which recesses the grippers enter to receive the sheets. It will be understood that the grippers are opened and closed at the proper times by suitable mechanism which need not be specifically referred to, as the particular form of delivery mechanism is immaterial to the present invention.

The rockers 3 and 4 preferably have flat under-surfaces and the successive openings referred to above are preferably controlled by plugs 55 in order that they may be closed or opened to adapt the mechanism for different sizes of sheets or for any other purpose. The exhaust producing means for the rockers may be furnished by suitable pumping mechanism, in the present case consisting of two pumps 56 and 57 supported upon the lower cross stay and connected to the rockers respectively by suitable piping as illustrated. The operation of the mechanism is clearly illustrated in Figs. 4 to 7 inclusive and Fig. 10. In Fig. 4 the parts are in their initial positions. In Fig. 5 the side standards 20 have moved downward so that the presser-foot reaches underneath the rear edge of the top sheet which has been raised by the suction produced in the rear rocker. With the parts in this position, illustrated in Figs. 5 and 10, the forward rocker is slightly rotated thus curling up the forward edge of the top sheet (Fig. 6) and then has an upward movement drawing up the front sheet 130

to an appreciable extent in which positions (Fig. 7) the sheet is seized by the grippers.

It will be seen that with rockers at two ends of the pile, the likelihood that two sheets will be delivered at a time will be very small, for should the rear rocker occasionally pick up two sheets, the probability that the forward rocker will do so at the same time is not large and if the forward rocker should 10 pick up two sheets the lower sheet would drop when the forward rocker rises being held in the rear by the presser-foot.

Various modifications may be made in the embodiment of the invention shown and described herein without departing from the spirit of the invention.

It should be mentioned that in many cases it will be possible to use the forward suction rocker 3 without the rear suction rocker 4 and the presser foot 29 and hence the invention is not to be regarded as necessarily limited to a construction in which the rear suction rocker and presser foot are embodied.

I claim as my invention:

- 25 1. In a device for feeding sheets from a pile, the combination of a rocker for operating upon the top of the pile near one end, bearings for the rocker, and arms adapted to lift the rocker, the bearings being slidable upon the arms and the arms being adapted to engage the rocker to turn it.
  - 30 2. In a device for feeding sheets from a pile, the combination of a rocker for operating upon the top of the pile near one end, bearings for the rocker, arms upon which the bearings are slidable, the arms being adapted to engage the rocker to turn it, and means to raise said arms.
  - 35 3. In a device for feeding sheets from a pile, the combination of a rocker for operating upon the top of the pile near one end, bearings for the rocker, arms upon which the bearings are slidable, a pinion upon the rocker, a rack upon one of the arms engaging the pinion, means to slide the bearings upon the arms so that the rack will turn the rocker, and means to raise the arms so as to raise the rocker.
  - 40 4. In a device for feeding sheets from a pile, the combination of a rocker located at one end of the pile having suction holes, an arm at either end of said rocker in which the rocker is journaled, a similar rocker located at the opposite end of the pile, an arm at either end of that rocker in which it is journaled, a presser-foot for one end of the pile, and means to raise the arms in which the rocker at the other end of the pile is journaled.
  - 45 5. In a device for feeding sheets from a pile, the combination of a member above one end of the pile having suction holes, levers in which the member is journaled, means to rock said member, a presser-foot, means to operate the presser-foot as the
- levers are moved, a similar member similarly mounted above another edge of the pile, and means to rock, raise and lower said member after the presser-foot has operated.
6. An apparatus for feeding single sheets from a pile, comprising in combination, a vertically adjustable table carrying the pile of sheets, a rear suction rocker mounted over the upper surface of the said pile near the rear edge thereof adapted to engage and roll or curl up the rear edge of the top sheet, a presser-foot located behind the rear suction rocker adapted to engage and grip the rear portion of the remaining sheets of the pile after the rear edge of the top sheet has been rolled or curled up, and a front suction rocker mounted over the upper surface of the said pile near the forward edge thereof adapted to engage and roll or curl up the front edge of the top sheet and then move so as to draw forward the rear end of the top sheet and bring the front edge of the said top sheet into position ready to be taken by grippers or other conveying mechanism.
7. An apparatus for feeding single sheets from a pile, comprising in combination, a vertically adjustable table carrying the pile of sheets, a rear suction rocker mounted over the upper surface of the said pile near the rear edge thereof adapted to engage and roll or curl up the rear edge of the top sheet, a presser-foot located behind the rear suction rocker adapted to engage and grip the rear portion of the remaining sheets of the pile after the rear edge of the top sheet has been rolled or curled up, a front suction rocker mounted over the upper surface of the said pile near the forward edge thereof adapted to engage and roll or curl up the front edge of the top sheet and then move so as to draw forward the rear end of the top sheet and bring the front edge of the said top sheet in advance of the remaining sheets of the pile, and a traveling gripper adapted to take hold of the front edge of the top sheet and deliver it on to the feed plate of the printing-press or onto suitable conveying mechanism.
8. An apparatus for feeding single sheets from a pile, comprising in combination, a vertically adjustable table carrying the pile of sheets, reciprocating standards, side arms pivoted to said standards, a rear suction rocker mounted over the upper surface of the said pile near the rear edge thereof in said side arms, said rear suction rocker being rocked by the lowering of the standards to roll or curl up the rear edge of the said top sheet, a presser-foot carried on the said standards adapted to engage and grip the rear portion of the remaining sheets of the pile after the rear edge of the top sheet has been rolled or curled up, a front suction rocker mounted over the upper surface of the said pile near the front edge thereof, said front suction rocker being adapted by a

backward movement to roll or curl up the front edge of the said top sheet, and means for raising said front suction rocker to draw forward the rear end of the top sheet and 5 bring the front edge of the said top sheet into position ready to be taken by the grippers, as set forth.

This specification signed and witnessed this 5th day of March, A. D. 1907.

FRED WAITE.
